BOOKKEEPING MACHINE

Fritz Bossert, Mannheim, Germany

Application January 13, 1930, Serial No. 420,610
In Germany December 22, 1928

2 Claims. (Cl. 235—3)

This invention relates to bookkeeping machines, cash registers and similar machines and more especially to machines automatically printing totals and subtotals on ledger cards and the like.

5 The principal object of the invention is to provide means for preventing the fraudulent employment of the impressions of totals and subtotals as impressions of normally entered amounts.

10 A further object is to provide means for partly obstructing the slot provided for introducing the normal ledger cards in total taking operations, the partly obstructed slot being only large enough to permit introduction of a card of smaller size. The invention is to be used with a bookkeeping 15 method for bookkeeping machines which consists in employing ledger cards, on the one hand, of normal size for printing amounts registered in the machine and totals and, on the other hand, ledger cards of smaller size for printing subtotals.

20 In the accompanying drawing wherein an approved embodiment of the invention is illustrated,

Fig. 1 is a plan view of a ledger card of normal size.

25 Fig. 2 is a fragmentary plan of a smaller sized card for printing subtotals.

Fig. 3 is a fragmentary side elevation of the machine showing the operating lever and the means connecting said lever to the pin or stop.

30 Fig. 4 is a horizontal section showing the means connecting the operating lever to the pin in top plan.

Fig. 5 is a detail view in elevation of the guide member for the connecting means.

35 A control lever of the type disclosed in this application is shown in the British Patent No. 365,164 (Fig. 10) and also in the pending U. S. application Serial No. 493,674 corresponding to said British patent.

40 Referring to the drawing in detail, the total control lever *l* which is common to machines of this type is secured to a shaft *f* and the latter is mounted in the wall *w* and in a bearing *g* fixed to the casing *h*. The lever *l* in the position shown in Fig. 3 is that which it assumes for addition operations 45 and it is movable to the two other positions indicated by the broken lines in Fig. 3, the two latter positions being known as "total" and "subtotal" positions. The total control lever is normally in the intermediate or "addition" position. From this position the lever is movable upwardly to the "subtotal" position in order to prepare the machine to print a subtotal and it is moved downwardly to the "total" position to prepare the machine to print a total. The means for printing 50 the ledger card and for shifting it in the differ-

ent lines do not form part of the present invention and may be of any known construction and are therefore not herein described.

An arm *d* is fastened at one end to the shaft *f* and being guided in the guide member *e* is bent so as to extend into the printing casing *q*, the opposite end of the arm terminating above the slot *s* provided for the introduction of the cards. The latter end of the arm *d* is pivoted at *c* to the pin or obstructing member *a* which latter is 10 mounted to slide vertically in a guide *b*.

5 In operation, when the total control lever *l* is in its intermediate position, as shown in Fig. 3, the slot *s* is unobstructed as the pin *a* is held in a position above it and ledger cards of normal 15 size, as shown in Fig. 1, may be freely inserted in the slot. If the lever *l* is set in its "total" position the arm *d* is swung in a clockwise direction and thus raises the pin *a* to a greater height leaving the slot *s* unobstructed. If, however, the lever 20 is moved to the "subtotal" position the arm *d* is rocked in the reverse direction moving the pin or stop *a* downwardly to a position in which it partly obstructs the slot *s* thereby preventing the introduction of a ledger card of normal size. The unobstructed portion of the slot lying to the left of the pin *a* in Fig. 3 is of sufficient width to permit 25 the introduction of a ledger card of smaller size than that illustrated in Fig. 2 but with the pin *a* in its obstructing position it is impossible to introduce a normal card of the width shown in Fig. 1 into the machine.

30 I claim:

1. In a machine of the class described, a kind 35 of operation lever, a total and subtotal position for said lever, an entrance slot for introducing ledger cards of small and of large sizes, printing means, stop means operated by said kind of operation lever and partially blocking said entrance slot in said subtotal position, said stop means 40 preventing the large size ledger cards from being introduced, but allowing said ledger cards of smaller size to be introduced for coaction with said printing means.

2. In a machine of the class described, a kind 45 of operation lever, an adding, a total and a subtotal position for said lever, an entrance slot for introducing ledger cards of small and of large sizes, printing means, stop means for said slot 50 adapted to be raised and to be lowered by said kind of operation lever and, in said subtotal position, blocking the side of the entrance slot opposite to said printing means.

FRITZ BOSSERT. 55
